UNITED STATES PATENT OFFICE.

RICHARD V. JOHNSON, OF MERIDIAN, TEXAS.

WIRE STRETCHER.

Application filed May 27, 1922. Serial No. 564,064.

To all whom it may concern:

Be it known that I, RICHARD V. JOHNSON, a citizen of the United States, residing at Meridian, in the county of Bosque and State 5 of Texas, have invented certain new and useful Improvements in Wire Stretchers, of which the following is a specification.

This invention relates to new and useful improvements in wire stretchers.

10 The object of the invention is to provide a simple, quick-acting device having a slide- able wire-stretching member actuated by a handle lever; together with gripping means thru which the wire is passed and which is 15 adapted to automatically engage and hold said wire against displacement when the wire-stretching member is being slid into position to stretch said wire.

A particular feature resides in the 20 operation of the gripping means with the wire-stretching member, whereby the wire may be drawn as tightly as is desired by the operation of the handle lever, without the necessity of removing or adjusting the de- 25 vice during the stretching operation.

Another feature resides in a spring- 30 pressed pawl carried by the handle lever for disengaging the gripping means when said lever is swung to stretch the wire.

35 A construction designed to carry out the invention will be hereinafter described together with other features of the invention.

The invention will be more readily under- 40 stood from a reading of the following spe- cification and by reference to the accom- 45 panying drawings, in which an example of the invention is shown and wherein:

Fig. 1 is a side elevation of a wire stretcher constructed in accordance with my inven- 40 tion, in operative position,

Fig. 2 is an enlarged detail of the wire- 45 stretching member,

Fig. 3 is a longitudinal vertical sectional 50 view of the same,

Fig. 4 is an enlarged detail of the grip- 55 ping means, a portion of the bracket being broken away,

Fig. 5 is a sectional view taken on the line 5-5 of Fig. 4, and

Fig. 6 is an enlarged detail of a portion 60 of the handle lever, showing the spring- pressed releasing pawl.

In the drawings the numeral 10 designates 65 a carrier bar, the outer end of which is re- duced to form a slide bar 11. The opposite 70 end of the carrier bar is provided with an

aperture 12 in which is connected one end of a chain 13 having a hook 13' on its free end. In operation the device is hitched to a fence- 60 post 14 by looping the chain around the same and engaging the hook 13 in one of the links thereof, as is clearly shown in Fig. 1.

Pivotedly mounted on the side of the carrier bar is a depending handle lever 15, the upper end of which is connected to an elongated link 16. The outer end of the link is pivoted to a dog 17 which is inclined outwardly thru a slot 18 in the top of a sliding jaw 19. The dog is pivoted within the jaw 19 and its lower curved edge is serrated 70 so as to rigidly engage a wire 20, said jaw and dog constituting the wire-stretching member. The jaw is slidable on the bar 11 by means of a longitudinal guideway 21 in its lower portion, which telescopes over said 75 bar, as is best shown in Fig. 3. One side of the jaw is provided with an elongated slot 22 extending the full length thereof, so that the said jaw may be removed from the wire after the stretching operation is completed. A guide roller 23 is disposed within the jaw outwardly of the dog 17.

Mounted on the opposite side of the carrier bar to the handle lever 15 and adjacent the inner end of the slide bar 11 is a removable bracket 24, the upper portion of which overhangs the top edge of said carrier bar. A screw 25 is passed thru said bar and bracket and provided with a thumb nut 26, whereby the bracket is removably secured in 80 place. That portion of the bracket surrounding the screw 25, together with the corresponding portion of the carrier bar, may be provided with corrugations to afford a more positive connection, if desired. Pivoted within the overhanging portion of the bracket is a spring-pressed pawl 27 co- 85 operating with the serrated edge of the carrier bar thereunder to form the automatic gripping means, as is best shown in Fig. 4.

Mounted on the pawl 27 and projecting laterally thru a vertical slot 28 is a pin 29 which extends into the path of the handle lever 15. A spring-pressed releasing pawl 30 is carried by the short arm of the handle lever in a housing 31 provided on that edge of the lever adjacent the pin 29, said edge having a notch 32 immediately above said housing. The said pawl is arranged so as to engage and ride under the pin 29 when the handle lever is swung to slide the jaw 19 outwardly to its extreme position, as is 100 105 110

shown in dotted lines in Fig. 1. The outer edge of said pawl is reduced and curved so as to readily ride under said pin; while the inner edge is substantially straight. When the handle lever is swung in an opposite direction, it is evident that the straight edge will abut the pin 29, thereby raising the pawl 27 and releasing the engagement of the gripping means. It is pointed out that the releasing operation is automatic and takes place when the sliding jaw 19 starts its inward, wire-stretching movement.

In operation it will be seen that the device is hitched to the fence post 14 or other object in a manner hereinbefore described. The wire 20 which is to be stretched is threaded thru the sliding jaw 19 and the gripping means, so that the end of the same is engaged between the serrated edge of the carrier bar and the pawl 27. When the wire is thus engaged by the gripping means, the handle lever is swung towards the post so as to slide the jaw 19 to its extreme outward position, as is shown in dotted lines in Fig. 1. It is pointed out that by such movement of the lever the pawl 30 rides under the pin 29, said pin being received in the notch 32. The stretching operation is accomplished by swinging the handle lever away from the post 14, whereby the dog 17 rigidly engages the wire and the jaw 19 is slid inwardly on the bar 11. It is pointed out that at the same time the jaw 19 starts its inward movement the releasing pawl 30 abuts the pin 29, thereby breaking the engagement of the pawl 27 with the wire, the latter may be easily passed thru the gripping means as it is stretched by the inward movement of the jaw 19. It is pointed out that the pawl 27 is spring-pressed, and as soon as the jaw 19 completes its inward movement and the dog 17 thereof releases the wire, said wire is automatically gripped by the pawl 27 and prevented from slipping while said jaw is being slid to its outward position to again engage and tighten the wire. It will be seen that the operation of the gripping means is automatic and the stretching operation may be continued until the wire is tightened to the desired extent.

After the operation the thumb nut 26 is loosened, whereby the bracket 24 may be slightly raised to permit the wire to pass from under the pawl 27, it being pointed out that the slot 22 is provided in the jaw 19 to permit said jaw to be easily removed from

said wire. By disconnecting the hook 13' the chain may be readily removed from the post 14 as is obvious.

Various changes in the size and shape of the different parts, as well as modifications, may be made without departing from the spirit of the invention.

What I claim is:

1. In a wire stretcher, an elongated carrier bar, a wire-stretching member slidable on said bar, a handle lever carried by said bar and connected with said member for actuating the same, gripping means located on said bar inwardly of said member, said means including a spring-pressed pawl co-acting with serrations on the upper edge of said bar for preventing the wire from slipping when not being stretched by said member, means carried by the handle lever for disengaging the pawl with the wire when said member is slid inwardly, and means for securing the bar to a fixed support during operation.

2. In a wire stretcher, a carrier bar having one end reduced to form an elongated slide bar, a wire-stretching member slidable on the last named bar, a handle lever pivoted to the carrier bar, an elongated link connecting the lever with said member, a bracket carrying a spring-pressed pawl overhanging the upper edge of the carrier bar, said pawl co-acting with serrations on said edge for gripping and holding the wire against displacement when the latter is not engaged by the wire stretching member, means on the handle lever co-operating with a lateral projection on said pawl for displacing the latter upwardly when the wire-stretching member is slid inwardly, and means for securing the carrier bar to a fixed support during operation.

3. In a wire stretcher, an elongated carrier bar having serrations, a wire stretching jaw slidable on the bar and having a slot along one side through which the wire may be removed laterally, a lever mounted on the bar and connected with the jaw for reciprocating the same, a vertically adjustable bracket mounted on the bar and overhanging the serrations, a spring pressed pawl mounted in the bracket over the serrations, means carried by the lever for operating the pawl, and means for connecting the bar with a fixed support.

In testimony whereof I affix my signature.

RICHARD V. JOHNSON.
